UNITED STATES PATENT OFFICE.

GEORGE EDWARD KINCH, OF QUIRINDI, NEW SOUTH WALES, AUSTRALIA.
AUTOMATIC CLOSURE AND DISINFECTING SEAT-CABINET FOR PAN-CLOSETS.

Specification of Letters Patent. Patented Mar. 11, 1919.

1,296,666.

Application filed June 26, 1917. Serial No. 177,006.

To all whom it may concern:

Be it known that I, GEORGE EDWARD KINCH, a subject of the King of Great Britain and Ireland, residing at "The Poplars," Quirindi, New South Wales, Australia, have invented certain new and useful Improvements in Automatic Closures and Disinfecting Seat-Cabinets for Pan-Closets, of which the following is a specification.

This invention relates to cabinets for pan closets and includes improvements in automatic seat aperture closures and disinfectant sprinklers operated by canting the seat panel which is mounted pivotally near its rear end, the canting movement being effected by the imposition of the weight of a person on and the raising of such weight from the seat.

The aperture closure is a two leaf sliding shutter supported in guide runners in a cover which underlies the seat panel, and its operating means comprise a linkage to the canting seat panel which brings the shutters together to close the aperture in the rising movement and moves them apart to open the aperture in the lowering movement of the seat panel. The disinfectant or deodorant sprinkler is a sheet metal reservoir of angular section mounted on the back of the canting seat and fitted with a bent drip tube which is connected into the top of said reservoir so that a drip of fluid disinfectant or deodorant is delivered only while the closet is in use. The sides of the cabinet and the cover are constructed of sheet metal, as also are the shutters and linkages and the disinfectant reservoir, and the fitting is such that when the closet is not in use the cabinet is effectively fly proof.

In the accompanying drawings, Figure 1 is a perspective view of the top of the cabinet with the parts above the cover and sides removed; Fig. 2 is an underneath plan illustrating the shutters, their sides, and the operating linkages. Fig. 3 is a longitudinal section through the upper part of the cabinet complete; Fig. 4 is a detail section illustrative of the mounting of the disinfectant dripper; and Fig. 5 is a transverse section through the upper sides of the cabinet, the cover, and the slides and portion of the operating linkages.

The body portion 10 of the case or cabinet is a sheet metal box with its top edges rolled as shown at 11. This box is open bottomed and is set over an earth pan. The cover consists of an apertured sheet of galvanized iron

12 having four carrier lugs 13 which set over the sides of the cabinet, and two rearward wings 14 which carry the seat pintles 36. This cover is hinged to the box 10 on pintles 47 and may be swung open to offer access to the pan. This plate 12 is stiffened by integral bent up rib pieces 15 at the side edges of the aperture, and it carries two slides 16 and 17 in which the shutter plates 18 and 19 are 65 movable transversely toward or away from each other. 20 is a wood stiffener bar. The slide shutters are upbent at each lateral edge as shown at 21 to form check stops coacting with the flanges or ribs 15 which are returned downward as shown in Fig. 5 and at the meeting edges are flanged to make an overlap or rabbet joint as shown at 23. The outer side edges 24 of the cover are inflanged between the carrier lugs 13 to set neatly 75 within the case sides (see Fig. 5).

The mechanism for operating the shutters 18-19 comprises two lever arms 26 and 27 fulcrumed at 28 and 29 on the rear part of the plate 12 and slotted in arcs as shown to 80 coat with the slide pins 30 which are fixed in the shutters 18-19, and to offer the necessary clearance to permit said shutters to be moved by the swinging movement of said arms 26 and 27 about their fulcra 28 and 29. 85

Each lever arm carries an angle lug 30^x on a free pivot 31 laterally disposed relatively to the fulcrum pins 28 and 29. The downwardly projecting lugs of these parts are pivotally connected at 32 to the forward ends 90 of curved push bars 34 and 35 secured at their rear ends to the seat panel 33. The seat panel is pivotally mounted at 36 in the wings 14. 37 is a filler plate which serves to close the gap between the back end of the seat 95 panel and the rear wall of the case, to prevent entrance of flies when the closet is out of use.

The disinfectant reservoir 40 is an angular section sheet metal box with a top filling cap 41 and a drip tube 42 which is constricted as indicated at 43 to limit the flow of liquid. This tube is connected to the top of the reservoir 40 so that no liquid passes into it when the seat panel 33 is tipped up by counterweights 33^a hung rearward of its pivots 36. Fig. 4 shows the disinfectant operating to sprinkle disinfectant into the rear part of the pan 44 when the seat panel 33 is canted down, as when in use. 100 105 110

The operation is as follows. When not in use the seat panel 33 is canted up (see

Fig. 3) by its counterweights 33^a, and the push arms 34 and 35 are thrust forward, forcing the linkage levers 26 and 27 inward and thereby closing the shutters 18 and 19 as shown in Figs. 2 and 5. The disinfectant is at the same time tipped back in the reservoir so that none flows through the tube 42 (see Fig. 3). When the weight of a person is imposed on the seat panel 33 it is brought to the level position (see Fig. 4), thereby causing the disinfectant to drip, and at the same time drawing back the arms 34 and 35 and thus spreading the levers 26 and 27 and so sliding the shutters 18 and 19 apart to offer an open aperture to the pan.

What I claim as my invention and desire to secure by Letters Patent is:—

1. An automatic shutter operating mechanism for pan closet cabinets having an apertured cover, a pivotally mounted apertured seat, shutters movable to open and close the aperture in the cover, and pivoted levers connected to said shutters and operable by movement of the seat to open or close said shutters, characterized in this, that a pair of arms are fixedly connected at one end to said seat with their other ends laterally offset from the pivotal axis of said seat, and the last mentioned ends of said arms are connected by direct connections to said levers to operate the same when the seat is moved about its pivots.

Copies of this patent may be obtained for five cents each, by addressing the "Commissioner of Patents, Washington, D. C."

2. Mechanism as claimed in claim 1, wherein the direct connection between each of said levers and the corresponding arm comprises a member pivotally connected both to the lever and to the arm, the pivots being at right angles to each other.

3. Mechanism as claimed in claim 1, wherein the apertured seat is pivotally mounted on said cover intermediate its rear and front edges, said arms being secured to the seat to the rear of the pivotal axis and extending forwardly to their points of connection with the levers.

4. An automatic shutter mechanism for pan closet cabinets having an apertured cover, a pivotally mounted apertured seat, and shutters operable by movement of said seat to open and close the aperture in the cover, characterized in this, that the side edges of the aperture in the cover are flanged and the side edges of the shutters are provided with flanges coacting with the flanges on the cover to form check stops, the meeting edges of the shutters being flanged to form a rabbet joint when the shutters are closed.

In testimony whereof I have affixed my signature in the presence of two witnesses.

GEORGE EDWARD KINCH.
